HANDLING APPARATUS

Pierre Jean Marie Theodore Allard, Eaubonne,
France, assignor to Societe Francaise de Con-
struction de Bennes Automatiques, Paris,
France, a French body corporate

Application January 18, 1950, Serial No. 139,181
In France January 19, 1949

5 Claims. (Cl. 212—92)

1

The present invention relates to a handling apparatus intended in particular for automatically feeding by means of a bucket: cupolas, furnaces and other like chambers, in such a manner that when the bucket has been loaded on the ground for example, the operator starts, by means of a single movement, the following successive operations: the vertical lifting of said bucket, the lateral translation of same up to the axis of the cupola, instantaneous opening of the bottom of the bucket for discharging the materials, the closing of the bucket and finally the return thereof to the original position.

This apparatus is of the type in which a bucket provided with hooking head is suspended to a carriage adapted to move along an inclined track by the action, in one direction of the weight of the system and of the slope of the track, and in the other direction of a pull exerted on the lifting cable connected to the bucket. According to the invention the track is provided with two abutments between which the carriage is adapted to move, said carriage being provided with a rocking beam which supports at one of its ends the device for hooking the bucket and acts at its other end on a locking device intended to retain the carriage at the highest point of its travel devices for reversing the direction of operation of the motor controlling the lifting winch being provided for acting on the one hand by the action of said rocking beam and on the other hand by the action of the tension of the cable.

Other features will become apparent from the ensuing description.

In the accompanying drawings which are given solely by way of example:

Fig. 1 is a diagrammatic elevational view of the device according to the invention,

Fig. 2 is a plan view corresponding to Fig. 1,

Fig. 3 is an elevational view of the bucket,

Fig. 3a is a side view corresponding to Fig. 3,

Fig. 3b shows the device in open position,

Figs. 4 and 5 are two views in vertical section at two different positions of the device for controlling the opening of the bucket,

Figs. 6 to 8 are three elevational views of the device for attaching the bucket to the carriage.

Fig. 9 is a plan view on a larger scale of the device for attaching the bucket to the carriage.

Referring to Figs. 1 and 2, 1 denotes any wall, framework or support, and 2 an inclined track formed for example by two channel bars which are open towards one another and spaced a certain distance apart and support a carriage 3 provided with rollers 4.

2

The track 2 is provided with two abutments 5 and 6 for limiting the movement of the carriage 3 in both directions. Through said carriage 3 passes a pivot 7, on which is adapted to rock a rocking beam 8 which supports at one end a hooking frame 9 adapted to retain a bucket 10. A pulley 11 mounted on the rocking beam 8 acts as a deflector for a cable 12 which is connected on the one hand to the bucket 10 and on the other hand to a winch 13 and is returned by a pulley or a set of pulleys 14 mounted on a stationary support.

At the end towards the abutment 5 of the track 2 is located a cupola 15 provided with an opening 16 for the bucket 10 to pass through.

The end of the rocking beam 8 opposite the pulley 11 can, when it rocks, act by means of a pedal 17 for example, on a reversing switch 18 that acts on the electric motor 13a of the winch 13.

A spring controlled abutment 19 mounted on the carriage 3 limits the amplitude of swing of the rocking beam 8 in the direction *f* and is furthermore adapted to cause a bolt 21 to rock about a pivot 20, said bolt being secured to a fork 22 connected at 23 to the abutment 19.

Said bolt 21, by pressing against an abutment 24 provided on the track 2, prevents the carriage 3 moving towards the left and retains it in the upper position. The locking is obtained when the rocking beam 8 is not exerting any force on the abutment 19, i. e. when the bucket is resting on the ground and does not act by its weight on the opposite end of the beam 8. The position of the stop 24 is such that, when the carriage 3 is pressing against it, it is located a certain distance on the left of its upper stop 6.

The bucket 10 shown in detail in Figs. 3, 3a and 3b is of the shape of a frusto-cone slightly open towards its lower end, or any other shape with a taper that favors the outflow of the material through its lower part.

It is provided with hinged flaps 25 of the shape of half-bottoms which are connected to a sliding weight 26 by means of a device described in detail in Figs. 4 and 5. The sliding weight 26 is fixed to the end of the cable 12 which passes along the axis of a head 27 provided with an annular bearing surface 28 and mounted on a handle-shaped frame 29 secured to the bucket 10.

On both sides of the bucket 10, two rods 30 which are secured to the movable sliding weight 26 and act as guides for same, are each extended to a head 31 and slide in tubes 32. Cross-members 33, secured to said tubes 32, are connected

to rods 34 for controlling the opening of the flaps 25.

Each tube 32 slides in guides 35 and 36 secured to the body of the bucket.

Each tube 32 is surrounded by a tube 37 which is secured to the body of the bucket and which supports at its lower part two pivots 38 on which are mounted two rocking levers 39 provided with rollers 40 and 41 at their ends.

Between the tube 32 and the tube 37 is located a sliding tube 42 which is provided at the lower part thereof with an annular bevelled flange 43 adapted to bear against a spring 44 which in turn bears against an inner bearing surface 45 of the tube 37, and at the upper part thereof with an annular flange 46 capable of abutting against the lower face of the guide 36. Said tube 37 is provided with recesses 47 into which can penetrate the upper rollers 40 of the rocking levers 39 and the tube 32 is provided with recesses 48 into which can penetrate the lower rollers 41 of the rocking levers 39.

The rocking levers 39 are intended to retain the tube 32 locked in the upper position, when their upper rollers 40 are held apart by means of the bevelled flange 43 of the tube 42, the lower rollers 41 then penetrating into the recesses 48 of the tube 32 (see Fig. 5).

In this position the tube 42 under the action of the spring 44, abuts with its flange 46 against the guide 36 and the recesses 48 of the tube 32 in its upper position engage the lower rollers 41.

The device for hooking the bucket 10 by means of its head 27 to the frame 9 is shown in Figs. 6 to 9.

The frame 9 is connected to the rocking beam 8 by means of shock absorbers 50 and carries a tube 51 that forms a guide for the head 28 of the bucket when said bucket is hooked (see Fig. 8) on pawls 52 oscillatably mounted on pivots 53 and which move apart when the head 28 passes and fall back again below its flange, thereby enabling said head to bear against them. The whole weight of the bucket 10 and its contents is thus supported by the hooking device and by the rocking beam 8 by means of the spring shock-absorbers 50.

The hooking device is furthermore provided with a lever 54 which is adapted to rock on a pivot 55 and which is provided, on the one hand with a projection 56 located below two pawls 57 secured to the pivots 53 of the pawls 52, and on the other hand with a crankpin 58 adapted to engage a counterweight 59 slidably connected by means of a groove 60, to a pin 61 secured to the track 2. Two stops 62 and 63 limit the swinging movements of the lever 54 in both directions.

It will be understood that, when the lever 54 swings in the direction β (Fig. 7) by the action of the counterweight 59 bearing against the crankpin 58, the pawls 57 are pushed away by the projection 56 and swing upwards, carrying with them in the same movement the pivots 53 and the pawls 52 which move apart to enable the head 28 to pass. The position of the counterweight 59 is such that, when the carriage 3 bears by the bolt 21 against the stop 24, (Fig. 1), the counterweight 59 is located slightly on the right of the crankpin 58 of the lever 54.

The winch 13, on the drum of which the lifting cable 12 is adapted to wind, is provided with a motor 13a, which can be electrically reversed, on the one hand by means of the reversing switches 18 hereinbefore mentioned, and on the

other hand by means of reversing switches of a so-called "cable slack" device.

Said device (Fig. 1) comprises an arm 64 which is adapted to rock about a pivot 65 and which is provided with a roller 66 constantly bearing against the cable 12. When said cable becomes slack, the lever 64 can rock and acts by means of a cam 67 on a reversing switch 68 controlling the motor 13a.

10 The device operates as follows:

The bucket 10 previously filled and placed on the ground is attached to the cable 12 by its sliding lever 26, the carriage 3 being retained in position by the bearing of its bolt 21 against 15 the abutment 24 of the track 2 and out of contact with the abutment 6.

When the motor 13a of the winch 13 is started, said winch winds the cable 12.

20 The carriage 3, by the action of the tension 25 of the cable, moves backwards against the upper abutment 6 and the crankpin 58 of the lever 54 bears laterally against the counterweight 59 which rocks about its pivot 61 (Fig. 6). The bucket moves upwards towards the carriage and 30 as the tension of the cable is exerted on the weight 28, the heads 31 of the sliding rods 30 lift and retain the tubes 32 in their upper position. Consequently, the lower rollers 41 of the 35 rocking levers 39 are engaged in the recesses 48 of the tubes 32 (Fig. 5).

At the instant when the head 27 of the bucket 10 comes into contact with the attaching frame 3, it engages in the tube 51 by moving the pawls 52 apart and said pawls then fall below the flange 35 28. Then as the cable 12 continues to lift the bucket 10, said bucket causes the beam 8 to rock in the opposite direction to β . The end of the 40 rocking beam 8 then actuates the reversing switch 18 by means of the pedal 17 and the winch 13 starts to rotate in the opposite direction.

As the winch 13 then pays out the cable, the 45 rocking beam 8 moves downwards into the horizontal position and bears against the spring abutment 19 which releases the bolt 21, and the 50 hooking head 28 bearing against the pawls 52 compresses the springs of the shock-absorbers 50 and moves the hooking device 9 downwards into its lower position. The sliding counterweight 59 55 escapes from the crankpin 58 and returns to its vertical position and the carriage 3 starts its translatory movement (Fig. 8).

At the end of its translatory movement, the carriage 3 abuts against the lower stop 5, the 55 bucket 10 being placed in the opening 16 of the cupola 15. The cable 12 continues to unwind and the sliding weight 26 of the bucket moves downwards by the action of its own weight 60 and carries with it as it moves the rods 30 and the head 31. At the end of its travel, the 65 sliding weight 26 bears against the tubes 42 of the bucket and compresses the springs 44. The rollers 40 are released and the rocking levers 39 may rock and unlock the tubes 32 which, 70 since they are no longer retained by the heads 31, fall abruptly (Fig. 4) and cause the half-bottoms 25 to open abruptly and the materials contained in the bucket to be instantly ejected therefrom, their fall being further facilitated by the downwardly tapered shape of the bucket 10.

Then, as the cable 12 becomes slack, the lever 64 rocks and reverses the direction of operation of the motor by means of the reversing switch 68.

75 The winch 13 winds up the cable again, the weight 26 moves upwards and closes the bucket,

the various elements of which return to the position of Figs. 3 and 5.

Then the carriage 3 returns with a translatory movement towards the upper stop 6 and when it reaches this point, the weight of the bucket compressing the shock absorber springs 50, the lever 54 assumes a position below the sliding counterweight 59. As the pull continues to be exerted on the cable, the bucket lifts the rocking beam 8 and the sliding counter-weight 59 which causes the unlocking lever 54 to rock in the direction f_1 , the projection 56 lifts the pawls 57 which, as they move, cause the pawls 52 to open and leave a free passage for the head 28. Simultaneously, since the rocking beam 8 has rocked in the opposite direction to f_1 , its rear portion actuates the reversing switch 18 and causes the winch 13 to rotate in the opposite direction.

As the winch 13 pays out cable, the rocking beam 8 of the carriage 3 returns to the horizontal position and the pawls 52 are held apart since the sliding counterweight 59 is still resting against the unlocking lever 54.

The bucket then becomes disengaged from the attaching device and moves downwards towards the ground. At the instant when the bucket touches the ground, the cable becomes slack and the carriage 3 moves slightly downwards again and bears with its bolt 21 against the stop 24. In this slight movement, the sliding counterweight 59 escapes from the crankpin 58 and releases the lever 54, thereby enabling the pawls 52 to fall down into their waiting position (Fig. 6). Simultaneously and by the action of the slack of the cable, the lever 64 rocks and causes the apparatus to stop, the apparatus then being ready for a fresh cycle.

It can be seen that, owing to these arrangements, the operation of the apparatus for loading cupolas or furnaces is entirely automatic from the instant when the operation for starting has been effected until the instant when the empty bucket is returned to the ground, this result being obtained with the use of a single motor.

Discharging is effected in an abrupt and easy manner, which ensures a satisfactory distribution of the material in the cupola, then the bucket closes immediately after having emptied its contents into the cupola and before effecting its return travel.

Both during the translation and during the emptying of the bucket, the same is not supported by the lifting cable which is always liable to break owing to wear, but by a mechanical device of greater strength than can be obtained with a cable.

Having now described my invention what I claim as new and desire to secure by Letters Patent is:

1. A handling apparatus for conveying a material from one point to another which comprises an inclined track, two abutments secured to said track, a carriage rolling on said track

between said abutments, a rocking beam mounted on said carriage, a hooking device carried by said beam at one of its ends, a bucket provided with a hooking head adapted to engage said hooking device, a locking device carried by said carriage and adapted to be engaged by the other end of said beam and to retain said carriage, a lifting cable passing on said carriage and connected at one end to said bucket and at the other end to a winch, an electric motor for controlling said winch and electric reversing switches connected to said motor and adapted to be operated one by the rocking motion of said rocking beam and the other by the tension of said cable.

2. A handling apparatus according to claim 1 wherein said locking device comprises a spring abutment, a rocking bolt controlled by said spring abutment and a stop secured to said track in a point substantially corresponding to the highest point of the travel of said carriage, and adapted to be engaged by said rocking bolt.

3. A handling apparatus according to claim 1 wherein said hooking device comprises a guide tube for said hooking head, rocking pawls adapted to engage under said hooking head within said tube, a rocking lever comprising a crank-pin acting on said rocking pawls and a counterweight slidably connected to said track and adapted to engage said rocking lever.

4. A handling apparatus according to claim 1 wherein said bucket comprises a sliding cross arm secured to the corresponding end of said lifting cable, two pivotally mounted half bottoms, sliding tubes controlling the motion of said bottoms and a releasable locking device for connecting said sliding cross arm to said sliding tubes.

5. A handling apparatus according to claim 4, wherein said releasable locking device comprises, on each side of the bucket, a rod housed in said sliding tube, secured at one end to said sliding cross arm and releasably connected at the other end to said half bottoms, links connecting said sliding tube to said half bottoms, a stationary tube secured to said bucket and surrounding said sliding tube, a second coaxial sliding tube on the upper end of which may bear said sliding cross arm and disposed between said first sliding tube and said stationary tube, a spring urging said second sliding tube towards said sliding cross arm, a cam carried by said second sliding tube and a rocking bolt adapted to simultaneously engage said cam at one end and said first sliding tube at the other end.
